F. NASILLO.

HORN FOR AUTOMOBILES OR OTHER VEHICLES.

APPLICATION FILED JUNE 4, 1915.

1,182,101.

Patented May 9, 1916.

UNITED STATES PATENT OFFICE.

FRANCISCO NASILLO, OF BROOKLYN, NEW YORK.

HORN FOR AUTOMOBILES OR OTHER VEHICLES.

1,182,101.

Specification of Letters Patent.

Patented May 9, 1916.

Application filed June 4, 1915. Serial No. 32,042.

To all whom it may concern:

Be it known that I, FRANCISCO NASILLO, a subject of the King of Italy, and a resident of Brooklyn, in the county of Kings and State of New York, have invented certain new and useful Improvements in Horns for Automobiles or other Vehicles, of which the following is a specification.

This invention relates to horns for automobiles or other vehicles.

The principal object of this invention is to provide a horn of the above character which is simple in construction and may be manufactured at a low cost.

15 A further object is to provide a horn which is manually operated and which emits a sharp, piercing, sustained sound, the sound continuing for an appreciable length of time after the operator has released the operating means.

Further objects and advantages will more fully appear from the following detailed description and the features of novelty will be particularly pointed out in the claims.

25 In the drawings illustrating my invention, Figure 1 is a longitudinal cross sectional elevation of my improved horn. Fig. 2 is an enlarged transverse section taken along the line 2—2 of Fig. 1 with the operating handle 30 shown extended laterally in position to flex the spring. Fig. 3 is an enlarged cross sectional view taken along the line 3—3 of Fig. 1. Fig. 4 is a fragmental rear elevation of the horn with the operating handle shown 35 in the position in which the spring is placed under tension.

Referring particularly to the drawings, my improved horn comprises the usual resonator 10 having an annular flange 11 extending therefrom, to which is suitably fastened, as by screws 12, a circular casing 13. Bound between the resonator and casing is a metallic diaphragm 14. Securely fastened to substantially the center of the diaphragm 45 is a contactor, which by the impingement thereon of a metallic knocker causes the vibration of the diaphragm thereby producing a piercing note. This contactor comprises a beveled head 15, which constitutes the contactor proper, and a comparatively thin arm 50 extending therefrom. The arm is suitably riveted to the diaphragm at two spaced points 16, 17, but is slightly spaced therefrom at those points by suitable means, such

as spacers 18. This arrangement renders the 55 contactor 15 slightly yieldable under the impingement of the knocker, hereafter to be described, and reduces the amount of friction therebetween, thus saving power, which is utilized in increasing the speed of contact 60 between the contactor and knocker. In this way the note emitted from the horn is rendered very piercing and sustained.

The knocker referred to is a circular rack 19, which is formed integral and concentric 65 with a comparatively massive fly wheel 20, and at all times contacts with the contactor 15. The fly wheel is rotatably mounted upon a horizontal shaft 21. The latter is suitably journaled in a vertical frame 22, which is 70 fastened within the casing 13 by means of screws 23.

The frame 22 is placed adjacent the outer end of the casing, and is of such width as to leave room for the fly wheel on the outside 75 thereof within the casing. The fly wheel is prevented from sliding off the shaft by means of a screw 24, which is screwed longitudinally into the end of the shaft, and a washer 25. The fly wheel is also formed 80 with a hub 26, and is kept in its vertical plane upon the shaft by means of a ratchet wheel 27, which is suitably fixed upon the shaft between the frame 22 and the hub. This function of the ratchet wheel, is, however, only incidental, the main function 85 thereof being to coöperate with a pawl 28, which is suitably fastened to the fly wheel, and other mechanism to be described, in imparting rotary motion to the fly wheel, and 90 thereby the knocker 19.

The motive power employed to produce the rotation of the fly wheel is a spiral spring 29, which surrounds the shaft within the frame 22. The spring is secured at one end 95 to the shaft, and at the other to the frame, at 30 and 31, respectively. The compression of the spring is effected manually, and to this end, the shaft is formed of such a length as to extend beyond the frame and through 100 an aperture in the center of a cover 32, which closes the casing. Adjacent the outer end of the shaft, on the outside of the cover, is formed a squared portion 33, upon which is mounted a handle 34 having a corresponding square aperture. Any suitable means may be employed to secure the handle to the shaft. Thus, a nut 35 may be screwed to the

threaded end of the shaft. The handle normally abuts a projection 35 extending from the cover.

In operating the horn, the handle 34 is turned through an arc of a circle, or the whole 360° to the other side of the projection, if desired, thus compressing the spring. As the ratchet wheel 27 is fixed to the shaft it turns therewith, while the fly wheel remains idle, the pawl 28, which is maintained in contact with the teeth of the ratchet wheel by means of a spring 36, slipping past the same. When the handle is released, the resultant recoil of the spring causes the same to fly back to its normal position, while an impulse is imparted to the fly wheel through the agency of the pawl and ratchet, causing it to revolve with great speed and so continues for an appreciable length of time after the release of the handle. As the fly wheel rotates, each tooth of the rack, constituting an individual knocker, impinges successively upon the contactor and causes it to vibrate at a great rate of speed. This vibration being communicated to the diaphragm, there is produced a piercing, sustained note, which pedestrians and others could not fail to note and heed.

It will thus be seen that I have provided a horn which is very simple in construction, easy of operation, and cheap to manufacture. The source of power is connected directly with the knockers, so that intermediate gearing and other complicating parts are eliminated, and the liability of the device getting out of order is materially reduced. Great speed may be imparted to the knockers with but slight manual effort, and the note emitted is very sharp, piercing, and sustained.

Having thus described my invention, I claim as new and desire to secure by Letters Patent:

1. A horn comprising a resonator, a casing, a diaphragm disposed between said casing and resonator, a beveled contactor secured to said diaphragm, a shaft mounted in said casing, a fly wheel rotatably mounted upon said shaft adjacent the diaphragm, a rack formed upon the fly wheel and contacting with said contactor, a spring, one end of which is attached to the shaft and the other to the casing, a handle secured to the shaft for turning the latter against the tension of said spring without actuating the fly wheel, and means for transmitting the motion of the shaft to the fly wheel when the handle is released to cause the vibration of the diaphragm whereby a note is emitted.

2. A horn comprising a resonator, a casing, a diaphragm disposed between said casing and resonator, a contactor secured to said diaphragm, a shaft mounted upon said casing, a fly wheel rotatably mounted upon said shaft adjacent the diaphragm, a circular

rack formed upon the fly wheel and contacting with said contactor, a spring, one end of which is attached to the shaft and the other to the casing, a handle secured to the shaft for turning the latter against the tension of said spring, a ratchet secured to said shaft, a pawl pivoted to the fly wheel coöperating with said ratchet, said ratchet imparting the impulse of recoil of the spring to the fly wheel when the handle is released, whereby continuous impingement of the contactor is effected, and a piercing note emitted.

3. A horn comprising a resonator, a casing, a diaphragm disposed between said casing and resonator, a contactor secured to said diaphragm, said contactor comprising a casing, longitudinally thereof, a fly wheel rotatably mounted upon said shaft, a circular rack formed upon one face of said fly wheel concentrically thereof, said rack contacting with said contactor, a spiral spring mounted upon said shaft, means for compressing said spring, and means for transmitting the impulse of the recoil of the spring, when the latter is released, to the fly wheel whereby motion is imparted thereto and the diaphragm is vibrated and a piercing note is emitted.

4. A horn comprising a resonator, a casing, a diaphragm disposed between said casing and resonator, a contactor secured to said diaphragm, said contactor comprising a beveled head and an arm extending therefrom, said head and arm being spaced from said diaphragm, a shaft mounted within the casing, a fly wheel rotatably mounted upon said shaft, a rack formed upon one face of said fly wheel, a spring mounted upon said shaft, one end of which is secured to said shaft and the other end to the casing, a handle secured to said shaft for turning the same and compressing the spring, and means for imparting the impulse of the recoil of the spring, when the handle is released, to the fly wheel whereby said contactor is vibrated by said rack, and a piercing note is emitted from the horn.

5. A horn comprising a resonator, a casing, a diaphragm disposed between said casing and resonator, a contactor secured to said diaphragm, said contactor comprising a head and an arm extending therefrom, said head and arm being spaced from said diaphragm, a shaft mounted within the casing, a fly wheel rotatably mounted upon said shaft, a rack formed upon said fly wheel, a spring mounted upon said shaft, one end of which is secured to said shaft and the other end to the casing, an operating lever secured to said shaft for turning the same against the tension of the spring, a ratchet wheel secured to said shaft, a pawl pivotally mounted upon said fly wheel and coöperating with said ratchet, said ratchet

and pawl serving to transmit the impulse of the recoil of the spring, when the lever is released, to the fly wheel whereby the latter is made to revolve at great speed and the 5 diaphragm vibrated whereby a piercing note is emitted from the horn.

Signed at Brooklyn, in the county of

Kings and State of New York, this 1st day of June, A. D. 1915.

FRANCISCO NASILLO.
